UNITED STATES PATENT OFFICE.

CAMERON E. ORNDORF, OF JOHNSTOWN, PENNSYLVANIA.

ATTACHMENT CORD.

Application filed May 8, 1926. Serial No. 107,600.

My invention relates to terminal connectors for flexible conductors, more particularly to attachment cords for domestic appliances.

5 It is among the objects of my invention to provide a terminal connector for appliances which comprises a minimum number of cooperating parts of insulating material having conductor elements and connecting terminals embedded therein and which shall be adapted for universal movement as and for the purpose as will be hereinafter set forth.

In the general use of domestic appliances, 15 particularly sad irons it has been common experience to break or rupture the flexible conductor cord attached to the terminal by the manipulation of the appliance resulting in the short-circuiting of the conductor terminals and frequently in the blowing out of line fuses.

Various forms of terminal conductors have been heretofore proposed to obviate these difficulties and most of these prior 25 types provided for relative movement of the portion of the connector to which the cord is attached with the terminal portion attached to the appliance, such movements being provided in a given plane.

30 It is the purpose of my present invention to provide a terminal connector which is designed to permit universal movement of the cord connecting element relative to the terminal connector.

35 In the accompanying drawing constituting a part hereof and in which like reference characters designate like parts, Fig. 1 is a side elevational view of an electric sad iron having a universally movable terminal connector embodying the principles of my invention attached thereto; Fig. 2 is a longitudinal sectional view through the terminal connector illustrating the manner in which the several parts are associated and further

40 illustrating the several connections of the conductor elements embodied in these parts; Fig. 3 is a cross-sectional view taken on the lines III—III, Fig. 2; Fig. 4 is a view partially in section and partially in elevation of the terminal member taken on the lines IV—IV, Fig. 2; Fig. 5 is a longitudinal sectional view of a modified form of terminal connectors; and Figs. 6 and 7 are cross-sectional views of the cooperating terminal connector members.

Referring to the several figures of the

drawing the structure embodying the elements of my invention comprises a terminal connector generally designated by the reference numeral 1, having a body portion of 60 insulating material such as wood, rubber, or any of the well known molding compositions suitable to be formed into the shapes illustrated. The member 1 comprises parts 2 and 3 provided with countersunk openings 4 65 adapted to receive screws 5 for joining them. The member 3 is provided with a cut-away portion 6 to provide a space for mounting a movable insulator 7, the latter being preferably of yoke shape for receiving a terminal bushing 8 in which the ends of a flexible cord or current-carrying conductor 9 are secured as by screws 10, Fig. 2.

Referring to Fig. 4 of the drawing the member 3 is provided with a pair of spring 75 contacts 11 and 12 having their surfaces 13 shaped complementary to the terminals 14 of the sad iron shown in dotted lines in Fig. 1. Conductors 15 and 16 extending through openings 17 and 18 are respectively 80 secured to the contacts 11 and 12 by screws 19. The conductors 17 and 18 are secured to terminals 20 and 21, Fig. 2 having apertures 22 provided therein for receiving a pair of trunnion-shaped terminals 23 of the 85 yoke member 7. The terminals 23 are connected by conductors 24, Fig. 3 to apertured terminals 25 and 26 of the yoke, which in turn yieldingly engage a pair of transversely projecting lead terminals 27 of the terminal 90 bushing 8, these being formed of some insulating substance, to provide an electrical connection with its cooperating member and to constitute a durable mechanical joint. The terminal member 26 comprises a nipple 95 adapted to receive a screw member 28 having an apertured end for receiving the terminal 27. The yoke member 7 is further provided with a slotted portion 29, Fig. 2 to permit the assembly of the terminals 27 100 therein.

The modified form of terminal connectors shown in Figs. 5, 6 and 7 comprise the parts 2 and 3 of Figs. 1 and 2 having conductors 15 and 16 and terminal posts 21 and 22. Instead of the sleeve 8 for securing the flexible cord 9, the latter is connected directly to a yoke 30 having conductors 31 secured to terminals 32 and 33, they being adjustable for assembly purposes. An insulating block 110 34 having conductors 35 and 36 projecting in the manner shown to constitute trunnions for

engagement with the terminals 21 and 22 and 32 and 33 of the members 1 and 30 respectively is interposed between the latter to provide a universally movable joint. The 5 elements of Figs. 5 to 7 inclusive are cheaper to manufacture than the corresponding parts of the connector elements shown in Figs. 2 to 4 inclusive.

It is evident from the foregoing description of my invention that a terminal connector made in accordance therewith provides a simple mechanical and electrically efficient connecting means for attaching the flexible conductor to electrical appliances 10 and that the several parts in cooperative relation provide universal movement whereby the cooperating elements and particularly the conductor connections are relieved of detrimental stresses and twisting as was the frequent cause of annoyance in prior art devices. 15

Although I have described the specific embodiment of my invention it will be obvious to those skilled in the art that various modifications may be made in the details of construction and in the shape and arrangement of the several cooperating parts without departing from the principles herein set forth. 20

I claim:

- 30 1. A terminal connector for flexible conductors comprising in combination a connector member provided with contacts for the terminals to which it is to be joined, a yoke of insulating material pivotally mounted thereon, and another terminal member pivotally connected to said yoke.
- 25 2. A terminal connector for flexible conductors comprising in combination a connector member provided with contacts for the terminals to which it is to be joined, a movable insulator pivotally connected thereto, and a terminal bushing pivotally connected to said insulator.
- 35 3. A terminal connector for flexible conductors comprising in combination a connector member provided with contacts for

the terminals to which it is to be joined, a movable insulator pivotally connected thereto, and a terminal bushing pivotally connected to said insulator, said connector, movable insulator and terminal bushing being adapted for universal movement. 50

4. A terminal connector for flexible conductors comprising in combination a connector member provided with contacts for the terminals to which it is to be joined, a movable insulator pivotally connected thereto, and a terminal bushing pivotally connected to said insulator, and relatively movable terminal connections for said connector, insulator and bushing to provide a current-carrying circuit and to permit universal movement of said parts. 55

5. A terminal connector for flexible conductors comprising in combination a connector member provided with contacts for the terminals to which it is to be joined, a movable insulator provided with trunnions adapted for engagement with said member and having conductors embedded therein, 60 and a terminal bushing for securing the respective ends of a flexible two-ply conductor, said bushing having extending terminals for engaging the embedded conductor of said movable insulator. 70

6. A terminal connector for flexible conductors comprising in combination a connector member provided with contacts for the terminals to which it is to be joined, a movable insulator provided with trunnions 75 adapted for engagement with said member and having conductors embedded therein, and a terminal bushing for securing the respective ends of a flexible two-ply conductor, said bushing having extending terminals for 80 engaging the embedded conductor of said movable insulator and said connector, insulator and bushing being adapted for universal movement without interrupting their respective connections. 85

In testimony whereof, I sign my name.
CAMERON E. ORNDORF. 90
